UNITED STATES PATENT OFFICE.

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MEASURED-SERVICE TELEPHONE SYSTEM.

Application filed July 9, 1923, Serial No. 650,348. Renewed April 21, 1927.

The present invention relates in general to measured service telephone systems, but more particularly to methods of providing measured service in automatic telephone systems; and may be considered as an improvement on Patent No. 1,475,612, issued to John Wicks November 27, 1923. The principal object of the invention in the instant case is the provision of improved means for controlling paystation mechanisms of well known type to automatically collect or refund deposited coins; and of improved means whereby the paystations may be controlled by operators in special cases as where a subscriber calls a long distance operator and is connected directly with another subscriber in a distant exchange, this type of connection being commonly referred to as a "two number call".

A further object of the invention is the provision of circuits for permitting subscribers of party lines, equipped with the above type of paystation equipment, to call back on their own line without the aid or intervention of an operator, such parties being given free service when calling parties on their own line.

Referring now to the drawings, Figs. 1, 2 and 3, when arranged in order with their corresponding lines at the ends thereof in alignment, represent a complete connection from a calling substation A to a recording operator in a distant exchange.

The equipment shown in Figs. 1 and 2 is in the exchange in which the substation A is located, while the equipment in Fig. 3 is located in the distant exchange.

Referring to Fig. 1, the substation A is one of four such substations and is provided with the usual talking apparatus and an automatic calling device or impulse sender S, and being on a paystation line is also provided with a well known type of coin collecting apparatus. It will be understood that the remaining substations on the line, of which only the ringers are shown, are provided with apparatus identical with that of substation A.

The line switch C, in which the line of substation A terminates, is a rotary line switch or one in which the wipers have no normal position but move in a forward direction only.

The paystation coin control repeater D is for controlling paystation equipment such

as that used at the substation A on both local and long distance calls, and in addition is provided with means for permitting subscribers of party lines, such as a subscriber at substation A, to set up connections to other subscribers on the same line.

The selectors E and E' (Fig. 2) are of the well known Strowger type and are wired in accordance with the usual two wire practice.

The secondary trunk repeater F is arranged to provide a holding circuit for whatever selector seizes it and is used primarily to avoid the necessity of having three conductors in the trunk line extending to the toll office, but in addition is provided with coin control circuits.

The relay group H in which the recording trunk Z terminates in the toll office, has associated with it the jack J at a toll recording operator's position. The operation of the circuits of the relay group H will be fully described later.

The cord circuit O (Fig. 3) is one that is used for answering calls coming into the toll recording operator as well as for completing toll connections.

The apparatus having been described in general, a detailed description of its operation will now be given. For this purpose it is assumed that the subscriber at substation A desires a toll connection. In order to initiate such a call he must first call the toll recording operator who then takes care of the call and sees to it that the desired connection is established. When the subscriber at substation A removes his receiver, a circuit is completed over the line conductors 1 and 2 for the line relay 7 of the line switch C. Upon energizing, line relay 7 closes at its armature 8 a circuit for the switching relay 3 and the stepping magnet 10 in series, and at its armature 9 connects a test wiper 12 to the above circuit at a point between the switching relay and the stepping magnet. The operation now depends upon whether the trunk line upon which the wipers of the line switch are standing is busy or idle. If the trunk line is busy there is a ground potential on the test contact with which the test wiper 12 is in engagement, switching relay 3 is short circuited, and the stepping magnet 10, which interrupts its own circuit

is operated in the manner of a buzzer to advance the switch wipers in search of an idle

trunk line. We may assume however, in the present case that when the call is initiated the trunk line upon which the wipers of the switch are standing is idle. Under these circumstances when the line relay 7 is energized, the switching relay 3 is not short circuited and the stepping magnet 10 is not operated because of the high resistance of the switching relay. The switching relay however is energized, grounds the test wiper 12 at armature 5 and at its armatures 4 and 6 disconnects line conductors 1 and 2 from the winding of line relay 7 and from ground respectively, and extends them by way of wipers 11 and 13, contacts 72 and 73, to conductors 14 and 16; conductor 14 extending by way of armature 19 and its resting contact, armature 23 and its resting contact, armature 28 and its resting contact, lower left hand winding of the repeating coil R, and the lower winding of relay 38 to ground, and conductor 16 extending by way of armature 18 and its resting contact, armature 22 and its resting contact, armature 25 and its resting contact, upper left hand winding of repeating coil R, upper winding of relay 38, and the winding of relay 42 to battery. Relay 38 is differentially wound and therefore does not energize over the above circuit. Line relay 42 however energizes and at its armature 43 completes a circuit for the slow acting relay 45. Upon energizing, relay 45 completes a holding circuit extending back to line switch C over the following path: Grounded armature 46 and its working contact, low resistance relay 64, release conductor 15, bank contact 77, wiper 12, armature 5 and its working contact, winding of switching relay 3, interrupter springs of the stepping magnet 10 to battery. It is understood that the above circuit is established before the line relay 7 has had time to de-energize. Relay 64 may be of about 50 ohms resistance and is low enough so that the multiples of the test contact 77 are made busy to other rotary line switches. The slow acting relay 45 also prepares a circuit for slow acting relay 51 at its armature 47, closes the circuit of the lower winding of the electro-polarized relay 29 at its armature 46, and at its armature 48 closes a contact in a special shunt circuit which shall be described later on. When the line relay 42 of the repeater was energized a bridge was closed across the trunk conductors 78 and 80 which may be traced as follows: conductors 78, upper right hand winding of the repeating coil R, upper winding of polarized relay 29, lower right hand winding of the repeating coil, conductor 71, armature 44 and its working contact to trunk conductor 80. Upon the closure of this bridge as above traced the line relay 81 of the first selector E is energized in the usual manner and closes the circuit of the slow acting release relay 83,

Upon energizing, the relay 83 prepares the first selector for operation in the vertical movement, and also closes the associated holding circuit extending back to the preceding switch, the circuit being traceable from grounded armature 84 and its working contact, resistance 100, release trunk conductor 15, over the previously described holding circuit extending back to the switching relay 3 of the line switch C. It will be seen that the holding circuit is now supplied with ground from two points, both from the grounded armature 46 in the repeater and from the grounded armature 84 in the selector, and it should be mentioned in this connection that the resistance 100 is approximately equal to the resistance of relay 64 of the repeater D. It follows that the circuit through relay 64 will continue to supply approximately one half of the current to the holding circuit after the line has been extended to the selector E and relay 64 will therefore remain energized.

Before proceeding further with the explanation, attention is called to the shunt circuit around the armature 44 and its working contact, which it may be mentioned are the impulse springs of the repeater D which control the operation of the selector E and succeeding switches. This shunt circuit extends as follows: from the armature 44, resting contact of armature 61 and the said armature, resting contact of armature 66 and the said armature, armature 48 and its working contact, and the working contact of armature 44. The contact of armature 48 is closed, but since relay 64 is energized armature 66 will be attracted and the shunt circuit will be opened at that point, it being clear from this that the shunt circuit will not interfere with the impulse springs represented by armature 44 and its working contact in repeating impulses.

Only the eighth, ninth and tenth contact levels of the selector E are shown. It is assumed in the present case that the contacts of the first eight levels connect with trunk lines which terminate in switches of the regular switch train, contacts of the ninth level connect with trunk lines terminating in special selectors such as the selector E', while contacts of the tenth level are connected with trunks terminating at recording operators' positions. The calling subscriber at substation A will therefore operate his calling device in accordance with the digit 0. By the operation of the calling device a series of ten interruptions is produced in the circuit of line relay 42 in the well known manner, which, at each deenergization retracts its armature 44 to interrupt the circuit of the line relay 81 of the first selector E. At the first deenergization of relay 42 an impulse of current is sent through the winding of the slow acting relay 51. Relay

51 in operating, at its armature 54 completes a locking circuit for itself which extends from the ground, resting contact of armature 26 of relay 24 and the said armature, and the armature 54 and its working contact through the winding of said relay 51 to battery. Relay 51 also at its armatures 52 and 55 and their working contacts, shunts both the upper and lower windings 10 of the differential relay 38. These circuit shunts are brought about in order to reduce the resistance and impedance of the switch control circuits to a minimum during the transmission of impulses. Proceeding now 15 to the selector E, at each interruption of its circuit the line relay 81 deenergizes and transmits a current impulse through the vertical magnet 89 to battery, the vertical magnet being operated in the usual manner to 20 raise the shaft of the switch step by step until the wipers stand opposite the tenth level in which are terminated the trunk lines extending to the operator's position. The slow acting relay 87 which is in series with the 25 vertical magnet is energized at the first impulse and retains its armature attracted while the vertical magnet is being operated. At the first movement of the shaft a circuit 30 is completed which extends from grounded armature 84 and its working contact, armature 88 and its working contact, off normal springs 99, interrupter springs 112 and the winding of stepping relay 90 to battery. The stepping relay 90 is accordingly energized and closes a locking circuit for itself 35 at its armature 91. At the end of the vertical operation of the switch the slow acting relay 87 is deenergized, thereby closing a circuit for the rotary magnet 93, the circuit being readily traceable from grounded armature 84 and its working contact, armature 88 and its resting contact, armature 92 and its working contact and the winding of magnet 93 to battery. Upon energizing, the rotary magnet 93 operates to advance the 40 wipers 101 to 103, inclusive, into engagement with the first set of bank contacts in the level opposite which they were raised in the vertical movement of the switch, and also breaks the locking circuit of stepping relay 90 at its 45 interrupter springs 112. Relay 90 therefore deenergizes and breaks the circuit of the rotary magnet 93, which accordingly retracts its armature and again closes the interrupter contacts 112 controlled thereby. The 50 operation now depends upon whether the test contact engaged by the wiper 102 is busy or not. If the test contact engaged by the wiper 102 is busy it will be grounded, and the stepping relay 90 will again be energized over a circuit which includes the test wiper 102, armature 96 and its resting contact, off normal springs 99, interrupter springs 112 and the winding of stepping relay 90 to battery. The energization of the stepping relay 55 results in another closure of the circuit of the rotary magnet, which advances the wipers of the switch into engagement with the next set of bank contacts, and at the same time breaks the circuit of the stepping relay. 60 This operation, by which the stepping relay 90 and the rotary magnet 93 are alternately energized and deenergized takes place very rapidly and will continue until an idle or ungrounded test contact is engaged by the wiper 102. Assuming that the trunk line extending to the recording trunk repeater F is the first trunk line of the group or at least the first idle trunk line, when the test wiper 102 arrives at the test contact 105, it will find no ground potential and the switching relay 94 which was connected in series with the stepping relay 90 upon the closure of off normal springs 99, and which until now has been short circuited will energize, with the result 65 that the trunk conductors 78 and 80 are disconnected from the windings of the line relay 81 and are extended by way of wipers 101 and 103, bank contacts 104 and 106 to the trunk conductors 149 and 138, through 70 springs controlled by armatures 115 and 116 of relay 113 and the upper and lower windings of line relay 118 to battery and ground, respectively. The line relay 118 accordingly 75 energizes and at its armature 120 completes the circuit of release relay 121. Upon energizing, relay 121 connects, at armature 122, a lead from generator Gen. to conductor 149 by way of armature 126' and its resting contact. This sends an audible signal back to 80 the calling subscriber to inform him that the call is successful. It is understood of course that this has nothing to do with signalling the operator but is merely done to simulate the practice of giving the calling subscriber 85 an audible signal whenever ringing current is sent out to ring the called subscriber's bell. As a further result of the energization of relay 121, armature 123 grounds the release 90 trunk conductor 140. This ground extends from the said armature 123, armature 128' and its resting contact, release trunk conductor 140, bank contact 105, wiper 102, armature 96 and its working contact, where 95 the circuit divides, one branch extending over the release trunk conductor 15 over the previously described path to maintain the switching relay 3 of the line switch C operated, and the other branch extending by way 100 of the winding of switching relay 94 of the selector E over the previously described circuit to battery to maintain the selector E in its operated position. It is understood of course, that this circuit is established before the slow acting release relay 83 of the selector 105 E has had time to deenergize. 110 Returning now to the repeater F, we find that the energization of the line relay 118 not only closes the circuit of the release relay 121 as before explained, but also at its 115 arm- 120 a

ture 119 and its working contact, places the back bridge relay 126 in bridge of the conductors 149 and 150 of the trunk line Z. The trunk line Z as before explained extends to the office in which the toll recording operator is located, and the effect of placing back bridge relay 126 in bridge of this trunk line will now be described. High resistance relay 168 of the relay group H is normally included in bridge of the conductors of trunk line Z as follows: from the lower conductor 150 of the said trunk line by way of the armature 172 and its resting contact, lower left hand winding of repeating coil R', resting contact of armature 167 and said armature, upper and lower windings of relay 168, upper left hand winding of the repeating coil and upper conductor 149. The high resistance relay 168 is accordingly energized in series with the back bridge relay 126 in the repeater F. The back bridge relay 126, however, is not energized at this time due to the high resistance of the said relay 168. Upon energizing, relay 168 closes at armature 169 the following circuit for the line lamp L: grounded working contact of armature 169 and the said armature, armature 163 and its resting contact, armature 152 and its resting contact to the lamp L and battery.

30 The operator upon noting the lighted condition of the lamp L inserts a plug of an idle cord circuit, the plug P for example, into jack J and thereupon the following circuit is closed for relay 154: from ground by way of relay 154, conductor 177, sleeve side of the jack J, sleeve of the plug P, resistance 176 to battery. Upon energizing, relay 154 closes at its armature 156 a circuit for relay 162 by way of the normally closed contacts controlled by armature 159, and at armature 155 the said relay closes a circuit for slow relay 158. Upon energizing, relay 158 shifts the circuit of relay 162 so as to include the armature 153 and its resting contact and armature 159 and its working contact. At the same time that the original circuit is closed for relay 162 a circuit is also completed for relay 173 by way of armature 161 and its resting contact. Relay 158, however, is energized shortly after and at armature 161 breaks the circuit of relay 173. The effect of the energization of relay 162 will now be described. Upon energizing, relay 162 extinguishes the lamp L at armature 163 and closes a circuit for relay 166 at its armature 164. Relay 166, upon energizing, opens a multiple point in the bridge of the conductors of trunk line Z for reasons that will be hereinafter described. Returning now to relay 154, this relay upon energizing, places a shunt around the greater part of the high resistance winding of relay 168 at armature 157. In the repeater F the effect of shunting most of the winding of relay 168 of the relay group H is that the resistance of the circuit

of back bridge relay 126 is lowered sufficiently to allow the said relay to energize. Upon energizing, relay 126 closes at armature 142 a circuit for slow acting relay 131. Upon energizing, relay 131 closes at armature 132 70 and its working contact a multiple point in the circuit of release relay 121. A further result of the energization of back bridge relay 126 is that it closes at armature 143 and its working contact a circuit for relay 125. 75 Upon energizing, relay 125 establishes a locking circuit for itself at armature 128', disconnects the lead from the generator Gen. at its armature 126' and at armature 127 closes a point in the circuit of relay 129 for 80 a purpose which will be pointed out subsequently. The operation of armature 128' not only completes a locking circuit for relay 125 as before described, but in addition also removes the shunt from the primary winding of the induction coil 137. With this condition existing there is a circuit completed from ground by way of working contact of armature 123 of relay 121 and the said armature, primary winding of induction coil 90 137, conductor 140, bank contact 105 over the previously described circuit, through the switching relay 3 of the line switch C and the stepping magnet 10 to the tone bus bar and battery. The tone machine T causes a 95 high frequency tone to be transmitted over the above described circuit through the primary winding of the induction coil 137, which is repeated to the secondary winding of said induction coil which, it will be noted, 100 is included in a loop comprising conductors 138 and 150, left hand windings of the repeating coil R', conductors 149 and 78, right hand winding of repeating coil R, and conductors 78 and 80. 105

The toll recording operator, having by this time thrown her listening key K is able to hear this tone and is in this manner informed that the calling subscriber is on a paystation line, and that any connection completed by her must be paid for before conversation is permitted to proceed. The operator now operates her tone cut off key, the operation of this key completes a circuit for relay 151, which upon operating, at armature 152 opens a point in the circuit of lamp L, at armature 153 opens the circuit of relay 162 and at the same time closes a multiple point in the circuit of relay 158. Relay 162 upon deenergizing, at armature 163 110 opens a point in the multiple circuit of relay 158, at the same time closing a point in the circuit of lamp L, opens the circuit of relay 166 at armature 164, and at armature 165 opens the bridge across the trunk line Z. Relay 168 in the said bridge accordingly deenergizes and opens a multiple point in the circuit of relay 158, but since the circuit of the latter relay is closed at armature 153 it does not deenergize at this time. A moment 115 120 125 130

later the slow acting relay 166 deenergizes due to the opening of its circuit at armature 164 as previously described and recloses the bridge across the conductors of trunk line Z, 5 relay 168 included in the said bridge immediately energizes and again at armature 169 closes a multiple point in the circuit of relay 158.

The operator will now return the tone 10 cut off key to normal position thereby breaking the circuit of relay 151. Relay 151 upon deenergizing completes the circuit of lamp L at armature 152, and at armature 153 opens a multiple point in the circuit of relay 158, at the same time closing the circuit of relay 162 by way of armature 159 and its working contact. Relay 162 upon energizing, opens the circuit of lamp L at armature 163 before the said lamp has become 20 fully lighted, at the same time closing a multiple point in the circuit of relay 158, closes at armature 165 a multiple point in the bridge across the conductors of trunk line Z, and at armature 164 closes a circuit for relay 166. Relay 166 upon energizing, opens a multiple point in the said bridge. This however, has no function at this time. It is now seen that whenever the tone cut-off key is operated the final result is a momentary opening of the bridge across the 30 trunk conductors of trunk line Z, the operation of which depends upon the time required for the slow acting relay 166 to fall back after its circuit is opened. The momentary opening of this bridge across the trunk line Z allows the back bridge relay 126 in the repeater F to deenergize momentarily. Upon deenergizing, the back bridge relay 126 opens at armature 142 the circuit of slow acting relay 131. It may be stated here that relay 131 in the repeater F is 40 slower to fall back than relay 166 in relay group H. Consequently the deenergization of relay 126 is of not long enough duration to allow relay 131 to deenergize. As a further result of the momentary deenergization of relay 126 a circuit is closed at armature 143 for the relay 134. This circuit extends from grounded working contact of armature 123 of relay 121 and the said armature, armature 128 and its working contact, armature 143 and its resting contact and the winding of said relay 134 to battery. Relay 134, upon operating completes 50 a locking circuit for itself at its armature 135 and at its armature 136 and its working contact places a short circuit around the secondary winding of the induction coil 137, thereby cutting the tone off.

The calling subscriber and the toll recording operator may now converse with each other in the usual manner, the talking circuit being outlined by the heavy conductors.

65 In case the call is intended for a sub-

scriber to whom connection can be extended without much delay the toll recording operator functions as a regular toll operator also and completes the connection. Assuming that such is the case, she tells the calling 70 subscriber to remain on the line while she calls the desired subscriber. To do this the operator inserts the plug P' in a suitable jack and thereafter takes the usual steps required to complete the connection in any 75 well known or desired manner.

Since the station A is equipped with a paystation it is necessary that the operator collect the coin or coins required to pay for the connection before conversation between 80 the subscribers is permitted. The operator will therefore, upon getting a response from the desired called party, inform him that he is about to receive a long distance call and to remain on the line. The operator 85 now informs the calling subscriber that she has obtained the desired party and requests the subscriber to deposit the proper coin. When the subscriber has deposited the proper coin the operator operates the collect 90 key. Upon operation of the collect key circuits are closed for relays 170 of the relay group H, relay 110 of the repeater F, and relay 40 of the repeater D. The circuit of relay 170 may be traced from ground 95 through springs 183 of the collect key, conductor 160 and the winding of relay 170 to battery. Relay 170 upon operating, at its armature 172 opens a point in the bridge extending across a trunk line Z by way of high 100 resistance relay 168 and at its working contact connects the conductor 150 to the conductor 182 which extends by way of springs 184 of the collect key to the winding of relay 178 to positive high potential battery 105 and ground. The opening of the bridge extending across the trunk line Z does not however cause the deenergization of back bridge relay 126 at this time as the relay 170 in operating, at its armature 171 completes 110 a holding circuit extending through only the upper winding of this relay. The circuit for relay 110 may now be traced from the grounded release trunk conductor 140, winding of relay 110, conductor 150, 115 armature 172 and its working contact, conductor 182, springs 184 of the collect key and the winding of relay 178 to positive high potential battery and ground. The resistance of relay 178 is very low compared with that of relay 110 and therefore 120 relay 178 is not energized at this time. Relay 110 however, operates and at its armature 111 completes a circuit for slow release relay 113. The operation of relay 113 is 125 effective to complete a local circuit to maintain relay 118 energized and to connect the high potential battery, which is present on the conductor 150, to conductors 149 and 138 by way of armatures 114 and 116 and 130

their working contacts. This high potential battery now flows over the trunk conductors 78 and 80. The current flow extending over the conductor 78 extends by way of the upper right hand winding of repeating coil R through the winding of high resistance relay 40 to the grounded release trunk conductor 15. Relay 40 operates over this circuit and at its armature 10 41 completes a circuit for slow release relay 20. The operation of relay 20 causes the conductors 78 and 80 to be extended by way of armatures 22 and 23 and their working contacts to conductors 16 and 14 extending 15 through the line switch C to conductors 1 and 2 of the subscriber's line. Tracing them separately from this point the conductor 1 extends by way of springs 74 of the paystation mechanism and the winding of the 20 polarized magnet to ground; conductor 2 extends by way of the switchhook and its upper contact through receiver R, transmitter T, and through springs 74 and the winding of the polarized magnet to ground. 25 This latter circuit is not necessary to the proper operation of the magnet, but is effective to short circuit the receiver during the collecting operation to prevent a disagreeable click being heard by the calling subscriber. The polarized magnet at the substation A operates to collect the coins and to open the springs 74 to disconnect the paystation from the line. When the polarized magnet at substation A is included in 30 the circuit with relay 178 at the operator's position the current flow is sufficient to cause this latter relay to also operate. Relay 178 is operated to complete a circuit for the lamp L³ which is lighted to inform the operator that the subscriber has actually 35 deposited a coin and that the collecting operation is being effected. The operator may now restore her collect key and again operate it in order to check up to see if the coin 40 has been properly collected. Assuming that it has, springs 74 at substation A will be opened and the relay 178 will not be operated and consequently the lamp L³ will not be lighted, thereby indicating that the coin 45 has been properly collected. Should the deposit of another coin be required the operator will repeat the operations above described. It may sometimes occur that the operator for one reason or another may wish 50 to refund the coin to the subscriber. She may do this by simply operating her refund key, which causes the negative high potential battery to be applied by way of the relay 180 out over the previously traced 55 circuit. The refunding operation is identical in all respects with that of collecting, with the exception that, since the battery is of negative potential the polarized magnet at the substation will be operated to refund 60 the coin.

Assuming the collecting operation to have taken place, the operator will now connect the subscribers in any well known manner.

When the connection is finally completed, the two subscribers converse with each other in the usual manner and after the conversation is completed both subscribers replace their receivers.

When the receiver is replaced at substation A, the line relay 42 deenergizes and 75 opens the circuit of the line relay 118 of the repeater F. Relay 118 in turn deenergizes and opens the circuit of the slow release relay 121. Relay 121 upon deenergizing, causes ground to be removed from release trunk conductors 140 and 15, causing the deenergization of the switching through relays 94 of the selector E and 3 of the line switch C. Relay 94 upon deenergizing, completes the circuit of release magnet 139 whereby the selector E is restored to normal, 80 and the switching relay 3 of the line switch C deenergizes and is therefore again in its normal position. In the repeater F the line relay 118 upon deenergizing, also at its armature 119 opens a point in the circuit of the back bridge relay 126. Since relay 126 normally maintains the high resistance relay 168 in the relay group H energized, this latter relay deenergizes, causing the slow release relay 158 to also deenergize. A circuit for supervisory relay 173 is now completed, 85 from working contact of armature 156 and the said armature, armature 161 and its resting contact, and the winding of supervisory relay 173 to battery. The supervisory relay 173 upon operating supplies ground and battery to the relay 180 in the cord circuit O which operates to light the lamp L⁴ to inform 90 the operator that a disconnection is desired. 105

It may be convenient at this time to mention that a similar operation of relays 173 and 158 took place when the circuit of relay 168 was broken while the coin was being 110 collected, but at that time the operation was of no utility and the relay 180 and lamp L⁴ in the cord circuit were not operated due to the fact that the operator had her listening key thrown.

The operator upon noting the lighted condition of the lamp L⁴, knows that the conversation has been completed and that the subscriber at substation A has replaced his receiver. Accordingly she removes the plug P from the jack J thereby opening the circuit of relay 180 as well as that of the relay 154. Relay 180 upon deenergizing extinguishes the lamp L⁴. Relay 154 upon deenergizing, opens at its armature 156 the circuit of relays 162 and 173. These two relays 120 accordingly deenergize. Upon deenergizing, relay 162 at its armature 165 opens the bridge from across the trunk line Z, and at 125 its armature 164, opens the circuit of relay 166. Relay 166 upon deenergizing, again 130

closes a bridge across the trunk line Z. All the relays in the relay group H are now deenergized, and the trunk line Z is in condition to be taken for use for a subsequent 5 call.

As previously pointed out the selector E has access, by way of bank contacts in its ninth level to a group of special selectors, such as the selector E'. These special 10 selectors are used for extending connections to the trouble and information operators, and are also used to select reverting call switches. These latter switches as is well known are used by calling subscribers of party lines 15 when connections are set up to call other subscribers on the same line. Since only this type of connection has to do with the invention, the manner of setting up connections to trouble and information operators will 20 not be described. In the description which follows it is assumed that a reverting call switch of the type disclosed in the Patent 1,553,951, issued to Martin L. Nelson, on Sept. 15, 1925, is the type of switch to which 25 the selector E' has access. The only change which need be made in the reverting call switch shown in the drawings of the above application is to place a resistance such as the resistance 100 or 100', in the holding conductor of this switch. The purpose of this 30 resistance is to prevent the deenergization of the relay 64 in the repeater D when the reverting call switch is seized, so that impulses 35 may be also transmitted to this switch without the deposit of a coin by the calling subscriber being required.

Keeping the above explanation in mind it will now be assumed that the subscriber at 40 substation A initiates a call to another subscriber on the same line. Upon the removal of the receiver at substation A the line switch C operates to find an idle trunk line terminating in a selector, such as the selector E. The calling subscriber now operates his 45 calling device in accordance with the digit 9. This time the selector E operates in the manner previously described to position its wipers opposite the contacts of the ninth bank level, after which the automatic hunting operation takes place to select an idle 50 special selector E'. Since the selector E' is an exact duplicate of the selector E, the manner of operation of this switch need not be described in detail. It is sufficient to say 55 that the calling subscriber now operates his calling device in accordance with the proper digit to position the wipers of the selector E' opposite a group of contacts to which are 60 connected reverting call switches of the above mentioned type. The automatic selection of an idle one of these reverting call switches takes place, after which the calling subscriber transmits the proper series of impulses 65 to cause the reverting call switch to select ringing current of the proper fre-

quencies to be later transmitted back over the calling line.

The calling subscriber now replaces his receiver causing the bridge across the trunk line at the repeater D to be opened. It follows therefore that the line relay in the reverting call switch deenergizes to bring about the application of ringing current to the called line, which is also the calling line. The above disclosed reverting call switch is 70 arranged to alternately transmit ringing current of the proper frequency to operate the bells of both the calling and called subscribers' stations. Now since the relay 64 in the repeater D has been maintained energized, the relay 33 is also in operated position, and the ringing current flowing from the reverting call switch now flows over the talking conductors of the selectors E' and E and of the repeater D, causing the alternating current relay 36 to operate. Relay 36 75 in operating, at its armature 37 completes a circuit for relay 17 which operates to disconnect the left hand windings of the repeating coil R from across the line conductors 14 and 16 and connects these conductors in multiple with the alternating current relay 36. It will be seen therefore that each time ringing current is transmitted over the above circuit the relays 36 and 17 will be 80 actuated to relay the ringing current directly to the called line.

When the called subscriber responds the ring cut off relay in the reverting call switch is operated. If the receiver is removed during a ringing period the cut off relay is operated over a direct current path extending by way of conductors 78 of the repeater D, working contact of armature 18 and the said armature, bank contact 73, wiper 13, working contact of armature 6 and the said armature, line conductor 2, through the talking equipment of the calling subscriber's station, the conductor 1, armature 4 and its working contact, wiper 11, bank contact 72, conductor 14, armature 19 and its working contact, conductor 80', and conductor 80. As soon as the cut off relay operates the relay 36 in the repeater D deenergizes to break the circuit of relay 17. Relay 17 upon retracting its armatures again permits a circuit to be completed through the line relay 42. If, however, the called subscriber removes his receiver during a silent period the relay 17 is in deenergized condition and therefore the line relay 42 of the repeater D will become energized and the ring cut off relay will be operated over a circuit extending by way of conductor 78, upper right hand winding of repeating coil R, working contact of armature 34 and the said armature, lower right hand winding of the repeating coil, armature 44 and its working contact to the conductor 80. The operation of the cut off relay in 85 the reverting call switch causes ground to be 90 95 100 105 110 115 120 125 130 135 140

removed from the release conductors 151 and 15. The switching relays 94' and 94 of the selectors E' and E and the switching relay 3 of the line switch C now deenergize. The deenergization of relays 94' and 94 cause circuits to be completed for the release magnets of selectors E' and E and these switches are therefore restored to normal. The deenergization of the relay 94' of the selector 10 E' also causes the circuit of the line relay of the reverting call switch to be broken and as a result this switch is also restored to normal. Relay 3 of the line switch C upon deenergizing again connects up the line relay 7, which, 15 since the called subscriber has his receiver off the hook, again energizes and in the manner previously described again causes the seizure of the now restored selector switch E.

The subscriber at substation A, who is the 20 calling subscriber no longer hearing the bell being actuated, will remove his receiver. Conversation may now proceed in the ordinary manner battery being supplied to both subscribers from the winding of relay 42 and 25 the lower winding of relay 38 of the repeater D.

When the conversation is terminated the 30 release of the apparatus will take place in the ordinary manner upon both subscribers replacing their receivers upon the switch-hooks.

The operation of the circuits when the subscriber at substation A sets up a connection to another subscriber's line will now 35 be described, and it will be first assumed that a connection of this kind is attempted without depositing a coin. When the receiver is removed at substation A the operations by which the line of substation A is 40 extended through the medium of line switch C and the repeater D to the first selector E are identical with those described in the previous case and will not be repeated. The operation of the selector E by which the 45 connection is extended to a second selector likewise has also been described, and in this case there is nothing new in the operation except that the wipers of the selector E are raised opposite one of the first eight levels, 50 in which are terminated trunk lines which extend to second selectors of the regular trunking system. These second selectors are not shown but are similar in all respects to the selector E' with the exception that the 55 resistance elements 100' are omitted. As soon as the selector E positions its wipers on the contacts of an idle trunk line the switching relay 94 energizes in the same manner as previously described, causing the line relay of the second selector to be bridged across the extended calling line. The line 60 and release relays of the second selector therefore energize. The release relay in operating connects direct ground to the release trunk conductor, since no resistance, such as

resistance 100 or 100', is included in this case and the relay 64 at repeater D is practically short circuited. This relay therefore deenergizes and at its armature 66 closes the previously described shunt circuit 70 around armature 44 of relay 42 and its working contact, thereby rendering the said armature 44 ineffective to open the bridge across the trunk conductors 78 and 80 when relay 42 is deenergized. When the calling subscriber now operates his calling device in accordance with the next digit and produces another series of interruptions in the line circuit, the resulting deenergizations of relay 42 will be of no effect and it will be apparent that the second selector can not be operated.

The difference in the two classes of switches used will now be apparent. All of those selectors which are required to be used in extending connections to operator's positions, or for completing reverting calls are provided with resistances similar to resistance 100 and 100', while those switches which are used only in connections to subscribers, have the resistance omitted. It follows that whenever an attempt is made to use a switch of the latter class under the circumstances just described, where no coin has been deposited, the relay corresponding to relay 64 of the repeater in use will be short circuited and will deenergize to disable the operating circuit extending to the switch ahead, thus preventing further extension of the connection.

A case where the calling subscriber at substation A deposits a coin before calling will now be described, and in this connection the process of collecting a coin at the termination of the conversation will also be described. The first operation is to deposit a coin in the collect mechanism. This causes the polarized magnet of the collect mechanism to be connected from the line 1 to ground. The coin may be deposited either before or after the receiver is removed. In either case the latter operation brings about the operation of the rotary line switch C whereby the line is extended to an idle selector switch such as the selector E (Fig. 2). When the line conductors 1 and 2 are connected, by the operation of line switch C, with the windings of the relays 42 and 38 of the repeater D the ground placed on the line by the deposit of a coin unbalances the differential relay 38 causing this relay to operate. It may be stated that the polarized magnet at the substation is of high resistance and does not materially interfere with the transmission of operating impulses or with the talking circuits, but is sufficient to unbalance and to cause relay 38 to energize as above described. Upon attracting its armature 39, relay 38 closes a circuit for relay 56, which relay establishes a locking cir- 125 130

cuit for itself at its armature 60. Relay 56 also grounds the holding circuit extending back to the line switch C at its armature 59, and its armature 61 opens the shunt circuit 5 from around the impulse springs represented by armature 44 and its working contact. This latter operation, it will be noted, permits any of the switches in the exchange to be operated no matter whether they are provided with resistances, such as resistance 100 or 100' or not.

The calling subscriber may now operate his calling device in accordance with the digits in the number of the desired station. 15 The selector E will respond to the first digit in the same manner as has already been described, and the second selector and any subsequent selectors (the number depending on the capacity of the system) and 20 the connector having access to the called line, will be operated in a well known manner to complete the connection after which suitable ringing mechanism is automatically operated to signal the called subscriber.

25 When the receiver is removed at the called station talking current is supplied to the transmitter thereat by the usual and well known back bridge relay of the connector, which upon energizing reverses the connections of the incoming trunk conductors in the usual manner. The essential elements of a connector used in this type of connection may be found in the Patent No. 1,551, 30 597, issued Sept. 1, 1925 to John Wicks, filed January 19, 1920. The direction of current flow in the bridge over the repeater D is therefore reversed causing the electro-polarized relay 29 to energize. Relay 29 upon 35 operating, at its armature 32 completes a locking circuit for itself, at its armature 31 shunts out its upper winding, and at armature 30 disconnects refund battery potential from connection with conductor 68' and connects collect battery to this conductor instead.

40 When the conversation is completed both subscribers replace their receivers. When the subscriber at substation A replaces his receiver the line relay 42 of the repeater D is deenergized. The deenergization of this 45 relay causes the bridge for maintaining the usual line relay of the connector switch to be opened at armature 44. It follows that the line and release relays of the connector deenergize. The release relay upon deenergizing completes the usual circuit for releasing the connector and also removes ground from the release trunk. The removal of ground from the release trunk, by 50 the connector, does not effect the release of the selectors as ground is fed forward by relay 56 of the repeater D. The relay 42 upon deenergizing, also at its armature 43 opens the circuit of relay 45. Since relay 55 45 is slow to release its armatures, a moment

tary circuit is completed from grounded armature 43 and its resting contact, working contact of armature 47 and the said armature and the winding of relay 51 to battery. Relay 51 upon operating, at its armature 54 completes a locking circuit for itself by way of armature 26 and its resting contact, and at its armatures 52 and 55 and their working contacts shunts out both windings of the differential relay 38. Relay 38 deenergizes and at its armature 39 opens the original energizing circuit of slow release relay 56. The relay 51 at its armature 53 also closes a point in the circuit of slow relay 24, this circuit being completed a 80 moment later by the retraction of armature 46 of relay 45. Relay 24 upon operating at its armature 27 opens the locking circuit of relay 56, and at the working contact of the said armature applies ground to the conductor 15, to prevent the release of the line switch C when the ground is removed from the conductor 15 a moment later by the restoration of the armature 59, at armature 26 opens the locking circuit of slow relay 90 51, at armatures 25 and 28 disconnects the talking conductors of the calling line from the left hand windings of the repeating coil, and at the working contact of armature 28 completes an operating circuit for the 95 polarized magnet at the paystation A and for the relay 49 in the repeater D. This circuit may be traced from positive high potential battery, resistance lamp 70, working contact of armature 30 and the said armature, conductor 68', armature 57 and its working contact, winding of relay 49, working contact of armature 28 and the said armature, resting contact of armature 23 and the said armature, resting contact of armature 19 and the said armature, bank contact 72 and wiper 11 of the line switch C, working contact of armature 4 and the said armature, springs 74 of the paystation device, and the winding of the polarized magnet to 100 ground. The energization of relay 49 causes the relay 51 to be maintained energized after ground is removed from its holding circuit by the operation of relay 24. The paystation magnet in operating, opens 105 its springs 74 causing the relay 49 to deenergize. Since the circuit of relay 56 was broken upon energization of relay 24, relay 56 now deenergizes and at its armature 57 breaks a second point in the operating circuit of relay 49 and the paystation magnet. The deenergization of the relay 49 also opens the circuit of slow release relay 51 and an instant later this relay also deenergizes, and 110 at its armature 53 opens the circuit of relay 24. Relay 24 upon retracting its armatures after a slight delay removes ground from the conductor 15 to permit the line switch C, selector E and the other selectors (not shown) used in the connection to be restored 115 120 125 130

to normal in the usual manner, and to permit the deenergization of relay 67. The operations just described are those which usually take place when the coin is being collected. It sometimes happens however, that the paystation magnet fails to operate fully and in this case when the relay 56 deenergizes and opens the operating circuits of relay 49 and the paystation magnet at armature 57, a circuit for relay 62 is closed at its armature 58. The operating circuit of relay 62 is intermittently opened and closed by the interrupter I and therefore periodically closes a new operating circuit for the paystation magnet and the relay 49 at its armature 63. It will be seen that the relay 49 and the paystation magnet will now receive the high voltage impulses periodically until the paystation magnet finally operates sufficient to collect the coin. The relay 49 operates to maintain the relay 51 energized to in turn keep the relay 24 energized, so that the line switch C and relay 67 will not be released or the collect circuit opened. When the coin is finally collected springs 74 open as before preventing further energization of the relay 49, consequently a moment later relay 51 deenergizes and at its armature 53 opens the circuit of relay 24. Relay 24 upon restoring, disconnects the holding ground from conductor 15 to restore the line switch C, selector E and the other selectors (not shown) to normal and to permit the deenergization of relay 67 in the manner previously pointed out. Relay 67 upon deenergizing, at its armature 68 disconnects the interrupter from the relay 62 to permanently deenergize this relay.

In case the calling subscriber did not answer it will be necessary to refund the deposited coin rather than collect it when the calling subscriber replaces his receiver, and this refunding operation will now be briefly explained.

Since the called subscriber did not answer the polarized relay 29 will not be energized and the negative or refund battery potential will therefore be present on the conductor 68. Now when the calling subscriber replaces his receiver the various relays in the repeater D operate in the manner previously described, but since the relay 29 is not energized negative battery potential will be present on conductor 68, therefore this refund battery instead of collect battery will be transmitted to the polarized relay at substation A to refund the coin. Immediately following the above operations the various relays in the repeater D and the line switch C will be restored to normal in the same manner as previously described.

What is claimed is:

1. In a telephone system, a calling subscriber's station provided with coin collect apparatus, a trunk line comprising two in-

ductively connected sections, means including a plurality of automatic switches for extending a connection from said station by way of said trunk line to an operator's position, a battery means at said position for connecting said battery to one section of said trunk, and means in said trunk responsive thereto for also connecting said battery to the other section to operate said apparatus.

2. In a telephone system, a subscriber's station provided with coin collect apparatus, an automatic switch, a selector switch, a trunk line divided into two inductively related sections and having one end terminating in bank contacts of said automatic switch and the other end terminating in said selector switch, means including said automatic switch and said selector switch for extending a connection to an operator's position, relays in said trunk for causing a metallic connection to be completed between said inductively connected sections, and means including a source of current at the operator's position for causing the operation of said relays, said source of current also being effective then to cause the operation of said coin collect apparatus.

3. In a telephone system, a subscriber's station provided with paystation mechanism and connected with a line terminating in a central exchange, automatic switches, a trunk line extending from bank contacts of one of said automatic switches in said exchange to another of said automatic switches in a distant exchange, trunk lines terminating in the bank contacts of said last switch and extending to an operator's switchboard at the distant exchange, means controlled by a subscriber for causing a connection to be set up via said automatic switches and certain of said trunk lines to said operator's switchboard, and means for causing current to be transmitted over said connection from said operator's switchboard to said paystation mechanism to collect or refund a coin as desired.

4. In a telephone system, a calling subscriber's line, a toll line, means including a series of automatic switches whereby said calling subscriber can connect said lines, paystation mechanism at the station on said subscriber's line, high voltage current sources of opposite polarity for collecting and refunding deposited coins, a circuit including a high resistance relay, means whereby the operator can connect either of said sources in said circuit, and means controlled by said relay for connecting the said subscriber's line in said circuit in parallel with said relay.

5. In a telephone system, a calling subscriber's line, a toll line, means including a series of automatic switches whereby said calling subscriber can connect said lines, paystation mechanism at the station on said subscriber's line, high voltage current sources

of opposite polarity for collecting and refunding deposited coins, a circuit including a high resistance relay, a second relay controlled by said first relay for connecting said subscriber's line in said circuit in parallel with said first relay, and a polarized magnet at said paystation included in the said parallel branch.

6. In a telephone system, a calling subscriber's line, a toll line, a toll operator's switchboard, means whereby said calling subscriber can establish a talking circuit between said lines, said means comprising serially related automatic switches, paystation mechanism at said subscriber's station, two sources of current at the operator's switchboard, and means controlled by the toll operator for applying current from either of said sources to the line conductors of the calling line to operate said mechanism.

7. In a telephone system, a calling subscriber's telephone line, an operator's switchboard, means whereby said calling subscriber can establish a talking circuit between said line and switchboard, said means including serially related automatic switches, repeating coils included in said talking circuit, and paystation mechanism at the subscriber's station, and means including sources of high potential current at said operator's switchboard controlled by the toll operator for collecting or refunding deposited coins, said means also including a relay for switching a portion of the talking circuit from connection with windings of said repeating coil to one of said current sources.

8. In a telephone system, a party line having subscribers' stations equipped with paystation mechanisms, means including series of automatic switches whereby a calling subscriber can establish connections to other lines only when a coin has first been deposited in said mechanism, means whereby connections may be established with an operator's position without the necessity of a coin being deposited, and means at the exchange whereby a calling subscriber can cause signaling current to be transmitted back on the same line without the deposit of a coin being required and without the assistance of an operator.

9. In a telephone system, a party line having substations provided with paystation mechanism, means including a series of automatic switches whereby a calling subscriber can establish a talking connection with an operator without depositing a coin, means comprising said series of automatic switches and another automatic switch whereby a calling subscriber may cause signaling current to be transmitted to another station on the same line without depositing a coin, and means comprising said first series of automatic switches and another automatic switch for establishing a talking connection

with another subscriber's line only when a coin has previously been deposited in said mechanism.

10. In combination with a measured service telephone system arranged to give calling subscribers access to an operator's switchboard without requiring the calling subscriber to deposit a coin in associated paystation mechanism and requiring such subscriber to deposit a coin in such mechanism before connection can be completed to other lines, subscriber controlled means for causing signaling current to be transmitted back over the same line to call other stations on the line without requiring the deposit of a coin in said paystation mechanism.

11. In a telephone system, a party line, paystation mechanism associated with each station on said line, a trunk line equipped with a paystation repeater, facilities for establishing talking connections via said trunk line to another line, means in said repeater for preventing such connection being established unless a coin has been deposited in the paystation mechanism, other automatic switches used for causing ringing current to be transmitted back to said paystation repeater, for signaling other subscribers on the same line, and means in said repeater responsive to said ringing current to also connect said current to the calling line for the purpose set forth.

12. In a telephone system, a multi-party calling line, paystation mechanism associated with each station on said line, subscriber controlled means for setting up connections to other lines only when a coin has first been deposited in said mechanism, and means for enabling a calling subscriber to directly set up a connection to cause another station on the same line to be signaled without depositing a coin.

13. In a telephone system, a calling line equipped with paystation mechanism, means including a trunk line for completing connections to other lines and to an operator's switchboard, a paystation repeater in said trunk requiring the deposit of a coin in said mechanism before connections can be completed to called lines, a source of current in said repeater for operating said paystation mechanism to dispose of deposited coins, means for rendering the paystation repeater ineffective to prevent the completion of calls extended to an operator's switchboard even though no coin has been deposited, a source of current at the operator's switchboard, and operator controlled means for connecting said last current source to the calling line to operate said paystation equipment.

14. In a telephone system, a calling line, paystation mechanism associated with said line, subscriber controlled means including

- a paystation repeater for setting up connections to other lines only when a coin has first been deposited in said mechanism, means for enabling a calling subscriber to directly set up a connection to an operator's position without the deposit of a coin being required, operator controlled means for then extending the connection to a called line, a source of current at the repeater for operating the mechanism when calls of the first class are completed and a second current source at the operator's position for operating said mechanism when calls are extended beyond the operator's position.
15. In a telephone system, a subscriber's line, a trunk line, an operator's switchboard, means including a series of automatic switches whereby a subscriber can establish

a talking circuit over said trunk to said switchboard, an energized relay in bridge of said trunk line for feeding talking battery to the calling line and for maintaining the release of the connection under control of the calling line, a source of current, a second relay for disconnecting said energized relay from connection with said trunk and for simultaneously closing a local holding circuit therefor, contacts on said second relay for connecting said source of current to the conductors of the calling line to cause the actuation of said paystation mechanism and operator controlled means for causing the actuation of said second relay.

In witness whereof, I hereunto subscribe my name this 6th day of July, A. D., 1923.

JOHN WICKS.
